UNITED STATES PATENT OFFICE.

JOHN T. MILLER AND JOSEPH A. DENNEY, OF MOUNT AYR, IOWA.

MITER-BOX.

SPECIFICATION forming part of Letters Patent No. 593,751, dated November 16, 1897.

Application filed July 26, 1897. Serial No. 646,003. (No model.)

To all whom it may concern:

Be it known that we, JOHN T. MILLER and JOSEPH A. DENNEY, citizens of the United States, residing at Mount Ayr, in the county 5 of Ringgold and State of Iowa, have invented a new and useful Miter-Box, of which the following is a specification.

This invention relates to miter-boxes, its object being to provide a box of this character 10 having saw supporting and guiding mechanism which can be easily and quickly adjusted to enable the saw to cut at any desired angle, either vertically or obliquely.

With this object in view the invention consists of the several details of construction and 15 combination of parts, as will be hereinafter fully described, and particularly pointed out in the claims.

In the drawings, Figure 1 is a perspective 20 view of a miter-box made in accordance with our invention. Fig. 2 is a rear elevation. Fig. 3 is a vertical transverse section on the line *a a* of Fig. 2. Fig. 4 is a sectional detail on the line *b b* of Fig. 3. Fig. 5 is a sectional detail on the line *c c* of Fig. 3. Fig. 6 is a plan view of a detached detail. Fig. 7 is a perspective view of a detached detail.

Similar reference-numerals indicate similar parts in the several figures.

1 indicates the bed-plate, which will preferably be of hard wood, although, if desired, it may be of metal, and the middle portion of the bed-plate projects forwardly in the form of a semicircle, as indicated by 2.

3 indicates the supporting-legs, which may be secured to the ends of the bed-plate in any suitable manner and are adapted to be secured to any suitable base-support. The back is formed of two sections, (indicated by

4,) which are spaced apart at their inner ends and secured to the rear edge of the bed-plate in any suitable manner. The inner portions of these sections 4 are inclined downward and toward each other at an angle of about thirty 45 degrees, as indicated at 5.

6 indicates a metal strip curved to fit on the edge of the semicircular portion 2 of the bed-plate and provided at each end with straight portions 7, adapted to be secured to the straight front edges of the bed-plate by

screws 8 or other similar fastening devices. This strip is provided with a slot 9, extending the entire length of its curved portion.

10 indicates a bar, its main portion being bent to semicircular form to be concentric 55 with the semicircular portion of the bed-plate, and this bar is provided at each end with a straight portion 11, adapted to be secured to the front edge of the bed-plate by screws 12 or similar fastening devices. The curved 60 portion of this bar is provided with a narrow slot 13 in substantially the same horizontal plane as the slot 9 in the metal strip 6. It is also provided with a wider slot, (indicated by 14,) which extends parallel to the slot 13. 65

15 and 16 indicate, respectively, the heads of two similar T-shaped castings, which are secured together and to the bed-plate at its rear edge midway the length thereof by bolts 17, and 18 and 19 indicate, respectively, the 70 stems of these castings. These stems project beyond the back of the miter-box and are rounded on their outer surfaces and screw-threaded at their ends, as indicated at 20. The upper face of the stem 18 is flattened, as 75 indicated at 21. The opposing faces of the heads 15 and 16 are cored out to form a V-shaped recess 22, and the opposing faces of the stems 18 and 19 are each provided with a semiglobular recess to form a socket 23, and 80 from which the V-shaped recess flares outwardly.

24 indicates a semicircular metal plate provided with a hub 25 to fit over the stems 18 and 19 to turn thereon. The lower portion 85 of this plate is provided with a straight edge, (indicated by 26,) and the other part of its edge is semicircular in form, the circle being struck from the axial center of the hub. A flange 28 projects rearwardly from this plate 90 entirely around it, and a slot 29 extends from a point midway the semicircular portion of the plate to the hub. Guides 30 are formed on the opposing sides of the slot 29 and project upwardly beyond the edge of the plate. The 95 opposing faces of these guides are concaved, as indicated at 31, and the edges thereof are beveled in opposite directions to present bearing-openings at each side of the guides.

33 indicates the rear saw-guide, which consists of a pin to fit in between the concaved faces of the guides to turn therein and also

to have free vertical movement. The upper end of this pin is shouldered and enlarged, as indicated at 34, and a slot 35 extends transversely through the pin for nearly its entire length, the upper end of said slot being enlarged, as indicated at 36, in order that an ordinary tenon-saw 37 may be inserted in the slot to work freely therein.

38 indicates a collar to fit over the stems 18 and 19 outside of the hub 25, and to the upper edge of this collar a bar 39 is secured to project rearwardly therefrom and to each side thereof, and this bar is adapted to seat upon the flattened portion 21 of the stem 18.

15 The upper portion of the hub 25 is cut away in order to permit the plate 24 to be turned on the stems 18 and 19 to the extent of about one-half of a revolution.

40 indicates wedges pivoted at their butt-ends on the opposite ends of the bar 39, with their thin ends opposing each other. The object of these wedges will be referred to hereinafter.

41 indicates a cap-nut to fit on the threaded ends of the stems 18 and 19 to hold the collar 38 and plate 24 in place.

42 indicates a rod, the rear end of which is reduced, as indicated at 43, and provided with a ball-shaped head 44 to seat in the socket 23 in the stems 18 and 19, and the reduced end portion 43 will play in the V-shaped recess 22, formed in the heads 15 and 16 of the castings. A head 45 is formed on the front end of the rod 42, the front end of which extends in close proximity to the inner face of the bar 10, and this head is provided with a vertical slot 46, extending through it, the slot being flared at both ends, as indicated at 47. A threaded stem 48 extends from the head 45 through the slot 14 in the bar 10, and a plate 49 is fitted over this stem and provided with lugs 50 on its rear face, which project into the slot 14. A thumb-nut 51 is fitted on the end of the threaded stem to hold the plate 49 in position, and the upper end of the plate is provided with a pointer 52.

53 indicates a tubular standard, from the lower end of which a flat bar 54 extends through the slot 46 and is pivoted therein on a pin or screw 54^a. The lower end of the bar 54 is pivoted on a pin or screw 55 between spaced ears 56 on the front end of a rod 57. The rear end of this rod is flattened, as indicated at 57^a, and the flattened end is pivoted 55 in a slot formed in a block 58 to permit the rod to swing in a horizontal plane, and the block 58 is pivoted between spaced ears 59 of a bracket 60 to turn in a vertical plane. The bracket 60 is firmly secured to the lower 60 straight edge of the plate 24.

61 indicates a transverse slot extending nearly the entire length of the tubular standard 53, and the upper end of this slot is flared, as indicated at 62, and its lower end is enlarged, as indicated at 63. A bar 64, having a flat upper face and a rounded lower face, extends through the enlarged portion 63 of

the slot 61, and its ends are flattened and widened, as indicated at 65, and these ends are seated in the slots 9 and 13, respectively. 70 Shoulders 66 are formed on the bar 64 to engage the opposing faces of the strip 6 and bar 10 to prevent longitudinal movement of the bar. A disk 67 is fitted within the standard and is provided with a loop 68, secured to its lower face, through which the bar 64 passes, with its flat face engaging the under face of the disk. The disk can therefore slide longitudinally of the bar, but is incapable of turning on it, and the disk will therefore always lie in a horizontal position.

69 indicates the front saw-guide, which is similar to the rear saw-guide 33, and is adapted to fit within the tubular standard 53 and be supported on the disk 67 when in its lowest position.

The inner ends of the back sections 4 extend close up to the flange 28 of the plate 24 and are curved to correspond with the curvature of said flange. To the inner end of the 90 right-hand section a metal plate 70 is secured in any suitable manner and provided with a threaded opening 71, in which the threaded end of a set-screw 72 works. This set-screw extends the entire length of the right-hand 95 section 4, the latter being provided with a suitable opening for its passage, and is provided at its outer end with a thumb-piece 73, by means of which it may be turned, and the function of this set-screw is to lock the plate 100 24 in any suitable position when required. A pointer 74 is secured to the right-hand section 4, and that part of a semicircular portion of the flange 28 which faces this pointer is provided with a suitable scale 75 to indicate the degrees of a portion of a circle in order that the saw can be set to cut obliquely 105 at any desired angle which may be indicated by the pointer 74 and scale 75.

A scale 76 is formed on the upper edge of 110 the bar 10 to indicate degrees of a portion of a circle, in order that the saw can be set to cut at any desired angle in a vertical plane.

When it is desired to use the saw to cut in a vertical plane, the plate 24 will be locked 115 against rotation by the set-screw 72 to hold the saw-guide 33 in a vertical position, and the saw can then be turned to cut at any desired angle, since the rods 42 and 57 are free to swing in a horizontal plane, and the angle desired may be accurately designated by the pointer 52 and the scale 76. The saw can be locked in position by tightening the thumb-nut 51. When it is desired to make an oblique cut, the set-screw 72 will be loosened in 120 order to permit the plate 24 to turn on the stems 18 and 19 in either direction, and the angle of obliquity can be accurately ascertained by means of the pointer 74 and the scale 75. When the saw-guides are turned from a vertical position, it is necessary that they shall be moved vertically in the guides 30 and the tubular standard 53, respectively, 125 in order to prevent injury to the teeth of the

saw by bringing them into forcible contact with the bed-plate, and this vertical movement is accomplished at one end by means of the wedges 40 and at the other end by means of the disk 67. As long as the saw is kept in a vertical plane at a right angle to the bed-plate it can be swung horizontally in either direction without changing the angle of the standard 53 relatively to the rods 42 and 57. 5 When, however, the saw is turned obliquely, the pivotal points of the rods 42 and 57 will be thrown out of vertical alinement, and when the saw is swung horizontally in either direction the bar 54 will be moved at its lower 10 end either toward or away from the rear of the box, according to the direction in which the saw is moved horizontally, and the standard 53 and saw-guide 69 will move in the opposite direction at their upper ends, and it is 15 to permit this movement that the standard 53 is pivotally connected to the rods 42 and 57 and that the disk 67 is free to move longitudinally of the bar 64.

It will be understood that changes in the 20 form, proportion, and the minor details of construction may be resorted to without departing from the spirit or sacrificing any of the advantages of this invention.

Having thus described the invention, what 25 we claim is—

1. In a miter-box, the combination with the bed-plate and a casting secured to the bottom thereof near its rear edge, said casting having a stem projecting beyond the rear edge, 30 of a plate mounted on the said stem to turn thereon, a saw-guide supported in said plate to turn axially therein, a rod having a hinged connection to said casting and extending to the front of the miter-box, means to slidably 35 support the front end of said rod, and a saw-guide supported by said rod substantially as described.

2. In a miter-box, the combination with the bed-plate, of a semicircular slotted guide- 40 plate secured to the front edge of the bed-plate, a casting secured to the bottom of the bed-plate near its rear edge and having a rounded stem projecting beyond the bed-plate, a plate pivoted on the said stem, a saw- 45 guide supported by the plate to turn axially therein, a rod having a hinged connection at its rear end to said casting and being supported at its front end in the slot of the said guide-plate, a tubular standard connected to said 50 rod in front of the bed-plate, and a saw-guide supported in said standard substantially as described.

3. In a miter-box, the combination with the bed-plate, of a semicircular slotted guide- 55 plate secured to the front edge of the bed-plate, a casting secured to the bottom of the bed-plate near its rear edge and having a socket and an outwardly-flaring recess formed therein, and a rounded stem projecting be- 60 yond the bed-plate, a semicircular plate pivoted on the said stem, a saw-guide supported by the plate to turn axially, a rod extending

at its rear end into the said flaring recess and having a ball-shaped head seated in said socket, said rod being supported at its front 70 end in the slot in the guide-plate, a tubular standard carried by said rod in front of the bed-plate, and a saw-guide supported in said standard to move longitudinally therein, substantially as described.

4. In a miter-box, the combination with the bed-plate and a casting secured to the bottom of the plate near its rear edge and having a rounded stem projecting beyond said edge, a semicircular plate mounted on said stem to 80 turn thereon, and having a scale formed on its periphery, a fixed pointer to coöperate with the scale, means to lock said plate against turning, a saw-guide supported in said plate to have axial turning, a rod hinged at its rear 85 end to said casting, means to support the front end of said rod in advance of the bed-plate, and a saw-guide supported by said rod, substantially as described.

5. In a miter-box, the combination with the 90 bed-plate and a casting secured to the bottom thereof near the rear edge, said casting having a stem projecting beyond said rear edge, said stem having a flattened portion on its upper face, a semicircular plate mounted on 95 said stem to turn thereon, spaced guides carried by said plate, a collar supported on said stem adjacent to the plate, a bar rigidly connected to said collar to engage the flattened portion of said stem, a saw-guide supported 100 between said spaced guides to move vertically and its lower end engaging said bar, and wedges carried by said bar on opposite sides of the saw-guide with their thin faces opposing each other, substantially as described.

6. In a miter-box, a rod extending below the bed-plate and supported at its ends to turn axially, a slotted tubular standard secured to said rod near its front end and extending above the bed-plate, a bar extending through the 110 slot in the tubular standard and supported at its ends against axial movement, a disk within the tubular standard connected to said bar to move longitudinally thereon and locked against rotary movement thereon, and a saw- 115 guide loosely fitted in the said standard and supported at its lower end on said disk, substantially as described.

7. In a miter-box, the combination with the bed-plate, of spaced guides at the rear edge 120 of the bed-plate and a tubular standard in front of the bed-plate, said guides and standard being supported to swing laterally in either direction from a vertical position, saw- 125 guides supported by the spaced guides and the standard, respectively, to have vertical movement therein, and devices to engage the lower ends of said saw-guides and move them within their supports when the latter are swung laterally from a vertical position, substantially as described.

8. In a miter-box, the combination with the bed-plate and a casting secured to the rear edge thereof, said casting having a stem pro-

jecting beyond said edge, of a semicircular plate mounted to turn on said stem, said plate having a straight edge on its lower portion, spaced guides carried by said plate, a slotted 5 semicircular bar secured to the front edge of the bed-plate, a rod connected at its rear end to said casting to turn axially therein and also to swing horizontally, said bar having a vertical transverse slot near its front end, a 10 bracket having spaced ears secured to the straight edge of the said semicircular plate, a second rod extending parallel to the first-named rod and pivoted at its rear end between said spaced ears to swing vertically and horizontally, and having spaced ears at its front 15

end, a tubular standard having a rod extending from its lower end through the slot in the first-named rod and between the spaced ears of the second rod, and being pivotally connected to both rods, and saw-guides supported 20 respectively by the tubular standard and said spaced guides, substantially as described.

In testimony that we claim the foregoing as our own we have hereto affixed our signatures in the presence of two witnesses.
